UNITED STATES PATENT OFFICE.

RAYMOND F. MAXWELL, OF LONG BEACH, CALIFORNIA.

REVERSIBLE VALVE.

1,405,310.

Specification of Letters Patent. Patented Jan. 31, 1922.

Application filed April 8, 1921. Serial No. 459,781.

To all whom it may concern:

Be it known that I, RAYMOND F. MAXWELL, a citizen of the United States, residing at Long Beach, in the county of Los Angeles and State of California, have invented certain new and useful Improvements in Reversible Valves, of which the following is a specification.

This invention relates to reversible suction valves and more particularly to that type of valve adapted to be attached to pumps of the rotary, centrifugal or plunger type whereby the pump may draw liquid from what was the discharge pipe into the suction pipe and vice versa.

The primary object of the invention is directed to the construction of a novel and improved reversible suction valve capable of being connected to various types of pumps and which is also adapted to be used as a reversing valve for steam engines and winches having piston valves to control the operation of the same.

Another and very important object of the invention resides in a reversible valve designed for installation in a liquid fuel supply system wherein the valve may be manually or automatically reversed to cut off the fuel supply and permit the same to be withdrawn from the system.

A still further object of the invention will be found to reside in the construction of a reversible valve which may be attached in various positions to different types of pumps or steam engines or installed in a liquid fuel supply system, including provision whereby the valve may be automatically reversed by a steam cylinder or by hand to cut off the fuel supply from the burners as in the case of fire when one of the pipes should break.

A still further object of the invention is the construction of a reversible suction valve capable of universal use in connection with various types of pumps and engines, compressors and other machinery and which will be extremely simple in construction, comprising but very few parts, positive and efficient in operation, adapted to be easily installed, and capable of being manufactured at an extremely low cost.

With these objects in view and others which will be manifest and suggested as the purpose and nature of my invention are revealed in the following specification and drawings, wherein I have shown one of the preferred embodiments thereof,

Figure 1 is a cross section of the reversible suction valve showing one position of the valve in dotted lines.

Fig. 2 is a section taken on the line 2—2 60 of Fig. 1.

Fig. 3 is a section taken on the line 3—3 of Fig. 1.

Fig. 4 is a diagrammatic view of the valve when installed in a fuel burner system. 65

Figure 5 is a detail side elevation of the reversing valve casing showing the steam cylinder partly in section.

Referring now to the drawings wherein like parts designate corresponding parts through the specification, 5 designates a cylindrical casing open at its top and bottom provided with closure plates 6, 7, suitably secured to the casing by screw fastening elements or bolts 8, 9, as clearly indicated by Fig. 1 of the drawing.

A suction port 10 near the bottom of the casing, and a discharge port 11 slightly above the center thereof is provided for connection with the usual suction pipe or conduit 12 and a discharge pipe 13 each of which are connected by screw bolts 14 to the sides of the casing whereby fuel for instance, may be pumped into and from the casing in the manner subsequently to be described. 80 An inlet port 15 connected to a supply pipe 16, and an outlet port 17 connected to a feed pipe 18 are also provided in the opposite side of the casing above the respective suction port 10 and discharge port 11 heretofore referred to. The suction and discharge pipes are of course directly connected to the pump, compressor or engine as the case may be whereby liquid fuel for instance may be pumped from a source of supply to a feed 90 system and vice versa when the valve is reversed as will now appear.

Within the casing 5 there is provided a valve designated 20 substantially one half the height of the casing and which has a central passage 21 and an enlarged annular passage 22 in the side thereof so that when the valve is in the position shown in full lines, Fig. 1, the ports 15 and 10 will be in communication to permit the liquid fuel to 100 be pumped into the casing through the port 11 and out through port 17 to a burner or feed system, as is readily understood.

A bracket 21^a secured to the top of the valve by fastening elements 22^a is connected 110 to a vertical operating rod 23, extending upwardly through the top plate 6 and a

packing gland 24 secured by fastening elements 24^a to the top plate, whereby a fluid, tight joint is had. The rod 23 carries an adjustable collar 25 to limit the vertical movement of the valve with respect to the top plate of the casing as suggested by Fig. 1 of the drawing when the said valve is reversed. The casing is also provided with additional right angle ports 26 which 10 may be blanked or plugged and thereby affording means whereby the casing may be more adaptable for installations with various types of pumps when it is desired to position the same to one side thereof for 15 convenient connection with a fuel supply system or other conduits. From the above construction of the valve, it will be readily seen that when the same is reversed to the dotted line position shown in Fig. 1 for 20 instance that the pump will draw the liquid fuel through the port 17 into the casing, through the passage 21 and into the port 10 which becomes open upon movement of the valve upwardly. The liquid will then 25 pass through the pump into the port 11 which then is in communication with the port 15 through the passage 22. As a practical illustration of one manner in which the reversible valve is adapted to be used, 30 particular attention is directed to Fig. 4 wherein the same is installed in a liquid fuel supply system, the operation of which will now be described in detail.

The diagrammatic view shown in Fig. 4 35 consists of a fuel oil heater 30 connected to a boiler 31 by a conduit system 32 whereby the liquid fuel is conducted to a burner 33 which is of the well known and usual construction. A discharge pipe 34 which 40 connects the fuel oil heater with the casing 5 of the valve, and a suction pipe 35 which connects a fuel oil tank 36 with said casing constitutes a part of the system having a pump designated 37 and the usual engine 45 38 whereby the liquid fuel is adapted to be pumped through the fuel oil heater and to the burner as is readily understood. A fusible link valve 39 is interposed in the steam pipe system connected to the boiler, 50 which system is connected by a conduit 40 to a steam cylinder 41 connected to the casing 5. If so desired the steam cylinder may be dispensed with but where it is desired to use the valve as a reversing valve, 55 the upper terminal of the operating rod 23 is loosely connected by a lever 42 to the stem 43 of the steam cylinder so that if steam is introduced in the said steam cylinder the valve may be reversed and the liquid fuel 60 withdrawn from the fuel oil heater.

Assuming now that the reversible suction valve is installed in the fuel supply system as shown in Fig. 4 so that it will work automatically, if one of the pipes in the supply 65 system should break and the fuel becomes

ignited, the fusible link would melt and thereby allow the steam under pressure to enter the steam cylinder and actuate the stem and reverse the valve from the full line to the dotted line position as shown in Fig. 1. This operation would cause the pump 37 to withdraw the liquid fuel from the oil heater 30 into the casing and permit the same to pass through the passage 21 into the port 10 and then through the ports 11, 15, to the pipe 35 and back again into the fuel oil tank. In this manner, it will be readily understood that as the liquid fuel is withdrawn from the system and back into the fuel oil tank, the fire will go out from lack of fuel. When the repairs have been made to the system, the valve may be reversed and of course fuel again pumped to the heater and conducted to the burners. In cases also where the suction pipe should become stopped up or clogged up with dirt for instance the reversing action of the valve would also force the obstruction out and the pump started again as before.

In the accompanying drawings, I have 90 illustrated my invention embodied in one form by way of example, and which in practice has been found to be highly satisfactory in obtaining the desired results. It will be obvious however that other embodiments 95 may be adopted and that various changes in the details of construction may be resorted to by those skilled in the art without departing from the spirit and scope of the invention. It is furthermore understood 100 that the invention is not necessarily limited or restricted to the precise elements shown except in so far as such limitations are specified in the subject matter being claimed.

Having shown and described my invention 105 what I now claim as new and desire to secure by Letters Patent of the U. S. is:—

1. A reversible valve of the class described comprising a casing, having suction and discharge ports in the body thereof, a valve 110 slideable within said casing and having a communicating side passage therein and automatic means for reversing the valve whereby the suction ports become discharge ports.

2. A reversible valve of the class described 115 comprising a cylindrical casing, open at its top and bottom, closure plates for said top and bottom, said casing having suction and discharge ports in the body thereof, a valve slideable within said casing having an enlarged communicating side passage and automatic means for reversing the valve whereby the suction ports become discharge ports.

3. A reversible valve of the class described 125 comprising a cylindrical casing, open at its top and bottom, closure plates for said top and bottom, said casing having parallel suction and discharge ports opening into the body of the casing, a valve having a central passage and an enlarged side passage slid- 130

able within said casing, and automatic lever operated means for reversing said valve whereby the suction ports become discharge ports and vice versa.

5 4. A reversible valve of the class described comprising a cylindrical casing open at its top and bottom, closure plates for said top and bottom, said casing having parallel suction and discharge ports out of alignment 10 with each other opening into the body of the casing, a valve having a central passage and an enlarged side passage slidable within said casing whereby to establish communication between the suction ports when the valve is 15 in one position and communication between a discharge port and a suction port when the valve is in a reversed position and automatic lever operating means for reversing said valve.

20 5. A reversible valve of the class described comprising a cylindrical casing open at its top and bottom, closure plates for said top and bottom, said casing having oppositely disposed parallel suction and discharge ports 25 out of alignment with each other opening into the body of the casing, a valve having a central passage and an enlarged side passage slidable within the casing for communication with the ports, a bracket secured to

the top of the valve, an operating rod connected to said bracket and automatic lever operating means for actuating said rod to reverse the position of the valve whereby the suction ports become discharge ports and 30 vice versa.

35 6. A reversible valve of the class described comprising a cylindrical casing open at its top and bottom, closure plates for said top and bottom, said casing having oppositely disposed, parallel suction and discharge 40 ports out of alignment with each other and opening into the body of the casing, and similar additional openings at right angles thereto, a valve having a central passage and an enlarged side passage slidable within the 45 casing for communication with the opposed ports, a bracket secured to the valve and bridging the central passage, an operating rod connected to said bracket and extending through a packing gland secured to the top 50 closure plate, and automatic lever operating means for actuating said rod to reverse the position of the valve whereby the suction ports become discharge ports and vice versa.

In testimony whereof, I affix my signature 55 hereunto.

RAYMOND F. MAXWELL.
